UNITED STATES PATENT OFFICE.

JOSEPH ELCOCK, OF MECHANICSBURG, PENNSYLVANIA.

GATE.

SPECIFICATION forming part of Letters Patent No. 358,653, dated March 1, 1887.

Application filed November 20, 1886. Serial No. 219,498. (No model.)

To all whom it may concern:

Be it known that I, JOSEPH ELCOCK, a citizen of the United States, residing at Mechanicsburg, in the county of Cumberland and State 5 of Pennsylvania, have invented new and useful Improvements in Gates, of which the following is a specification.

This invention has for its objects to improve the construction of swinging gates; to provide 10 novel means for supporting a gate and permitting it to easily swing open and shut; to provide novel means for automatically closing the gate when opened and released by the person passing through the gateway; to provide novel 15 means for enabling a person on horseback to conveniently open a gate and pass through the gateway without dismounting, and to provide novel means for raising the outer ends of a centrally-hung swinging gate, so that the gate 20 can be easily opened in snowy weather. These objects I accomplish in the manner and by the construction and combination of devices hereinafter described and claimed, reference being made to the accompanying drawings, in 25 which—

Figure 1 is a side elevation of a gate hung centrally between its ends and embodying my invention. Fig. 2 is a vertical sectional view taken on the line $x-x$, Fig. 1; Fig. 3, a side elevation showing a gate hung at one end according to my invention; Fig. 4, a sectional elevation of Fig. 3; Fig. 5, a sectional view on the line $y-y$, Fig. 3; Fig. 6, a detail plan view of the lower stationary bearing-plate for supporting the gate, showing the convoluted spring; Fig. 7, a detail inside plan view of the upper rotary disk to which the gate-post is secured; Fig. 8, a view similar to Fig. 6, showing a modification of the invention.

In order to enable those skilled in the art to make and use my invention, I will now describe the same in detail, referring first to Figs. 1 and 2 of the drawings, in which—

The numeral 1 indicates a circular bearing-plate of metal mounted on the upper end of metal posts 2, that are to be sunk in the ground so that the plate will lie slightly above the surface of the latter, said plate being secured to the underground metal posts by headed bolts 3, passing through the plate and the heads on the posts. The bearing-plate is provided at its center with an orifice, 4, for the passage of

a center bolt or pin, 5, and with a central socket, 6, formed by an annular vertical flange, 7, and said plate is also provided with two concentric flanges, 8 and 9. The rotatable circular disk 10 is provided with a central orifice, 11, and a central hub, 12, which sits in the socket 6 of the lower bearing-plate, and said disk is also provided with two concentric flanges, 13 55 and 14, resting on the flanges of the bearing-plate. The center bolt or pin, 5, is provided with a head at its lower end and a slot at its upper end, and said pin extends through the orifices of the bearing-plate and disk, and is secured by a wedge, 16, passing through the slot of the pin and bearing against a washer resting upon the top surface of the rotary disk in such manner that the bearing-plate and disk can be tightened together to compensate for wear 60 and prevent loose play of the parts by tightening up the wedge.

The gate-post is rigidly secured to the rotary disk, and, as here shown, this gate-post comprises two standards, 17, which converge 75 together at their upper ends, where they are secured by a transverse bolt, 18. The lower ends of these standards are provided with attached metal plates 19, secured by bolts 20, and having flanges or feet 21 at their lower 80 ends, which are secured to the rotary disk by bolts 22. The upper end of the post is provided at each side with a lateral perforated lug, 23, and to the rotary disk are secured two inclined brace-rods, 24, having their upper 85 ends screw-threaded and passing through the lugs and secured by screw-nuts 25, for the purpose of steadyng and bracing the gate-post and holding it securely in a perpendicular position.

The gate is composed of two series of horizontal slats, pivoted, respectively, at their inner ends to the standards composing the gate-post, and at their outer ends pivoted, respectively, to upright bars 26. In the upper end 95 of the gate-post is journaled a crank-shaft, 27, sustained by a bracket, 28, secured to the post, and on the crank-shaft, between the post and the bracket, is mounted a windlass or drum, 29, to which are connected the ends of 100 chains or cords 30, the other ends of such chains or cords being secured to the lower end portions of the uprights at the outer ends of the slats composing the gate. By turning the

crank-shaft, through the medium of its handles, in the proper direction, the chains or cords will be wound on the windlass or drum, and the outer ends of the gate be thereby elevated, so that the gate can be opened and closed with ease during snowy weather. When the outer ends of the gate are raised, as stated, the crank-shaft is locked by a locking-pin, 31, 5 for a rest for the crank-handle of the shaft, passed through a hole in the bracket, to afford so that the gate can then be conveniently swung in either direction for the purpose of opening the gateway. A person on horseback can ride 10 up to the gate, operate the crank-shaft, and lift the outer ends thereof, and thus swing the gate without inconvenience and without dismounting. If it becomes necessary to pass a vehicle or load through the gate—such as a grain 15 binder and harvester—which may be wider than the distance from the central gate-post to one of the outer ends of the gate, it is only necessary to withdraw the wedge from the center bolt or pin, when the entire gate and its 20 rotary disk can be removed, thus opening the gateway from fence post to fence post.

For the purpose of automatically closing the gate after it has been opened, I arrange between the bearing-plate and the rotary disk a strong and substantial convoluted spring, 32, 25 one end of which is secured to the rotary disk and the other end to the bearing-plate in such manner that when the gate is opened the rotary disk, acting as a lever, will place the spring under increased tension, and when the gate is released by the person after passing 30 through the reaction of the spring will close the gate by drawing the rotary disk back to its normal position. The spring is preferably located in the space between the two concentric flanges of the bearing-plate and the rotary disk. The bearing-plate is provided with a 35 segmental slot, 33, for the passage of a bolt or pin to brace the gate and prevent its sagging when the gate is hinged at one end, as in the modification, Fig. 3. This construction admits of the gate's being hinged centrally between its ends, as in Figs. 1 and 2, or being 40 hinged upon one end, as in Fig. 3, through the medium of bearing-plates and rotary disks of 45 the same construction.

As shown in Fig. 3, the bearing-plate 1, rotary disk 10, and gate-posts 17 17 are all substantially of the same construction as described with reference to Figs. 1 and 2. 50 Where the gate is swung from one end, it is desirable to provide means whereby the outer end of the gate will not sag, and to accomplish this a screw bolt or pin, 34, is extended through the segmental slot of the bearing-plate and through the rotary disk, and is provided at its upper end with a screw-nut, 35. A vertical brace-rod, 36, encircles the screw-bolt beneath the said nut, and is secured at its upper end to the top horizontal beam of the gate. 60 Between the end of the brace-rod secured to the bolt or pin 34 and the end of the plate 19

secured to the post a wedge, 37, is extended through a slot in the bolt, for the purpose of tightening the bolt or pin 34 and holding the rotary disk and bearing-plate in close contact, 70 to compensate for wear and to prevent loose play between the parts.

For the purpose of operating the gate with ease and facility I may employ friction-rollers 38 between the bearing-plate and the rotary disk, as shown in Fig. 8. These friction-rollers may be mounted in brackets and located in the spaces between the two concentric flanges 8 and 9 of the bearing-plate. Where this construction is used, the spring 80 referred to will be located in the space between the inner concentric ring, 8, and the annular central flange, 7, of the bearing-plate.

Heretofore a railway gate has been secured to a center post adapted to rotate in a step and provided with a spring connected with the step and the post, combined with levers operated by a train, whereby the gate can be automatically opened and closed. In another instance a gate has been composed of slats 90 pivoted at one end to fence posts or bars and at the other end to vertical rails, so that the gates can be opened by swinging them in a vertical plane; and in another instance a gate has been composed of rails secured to a post, 95 which at its lower end is attached to a bearing-plate adapted to rotate on a lower stationary bearing-plate. Such features are not, therefore, broadly claimed.

Having thus described my invention, what I claim is—

1. The combination of the lower stationary bearing-plate having a central socket formed by an annular vertical flange, and provided at its outer edge with an annular flange, with the 105 rotatable disk having a central depending hub fitting the socket of the bearing-plate, a center bolt or pin for connecting the plate and disk, a gate-carrying post secured to the disk, and a spring located between the plate and disk, 110 with one end connected with the bearing-plate and the other end connected with the rotary disk, substantially as described.

2. The combination of the lower stationary bearing-plate having a central socket formed 115 by an annular vertical flange, and provided with an annular vertical flange at its outer edge, with the rotatable disk having a central depending hub fitting the socket of the bearing-plate, a center bolt or pin for connecting 120 the plate and disk, and the gate mounted on the disk, substantially as described.

3. The combination of the lower stationary bearing-plate having a central socket formed by an annular vertical flange, and provided 125 with an annular vertical flange at its outer edge, with the rotatable disk having a central depending hub fitting the socket of the bearing-plate, a headed center bolt or pin extending through the plate and disk and having a 130 slot in its upper end, and a wedge extending through the slot, and a gate rigidly connected

with the rotatable disk, substantially as described.

4. The combination of an underground metal post comprising a horizontal head and pendent legs, a lower stationary bearing-plate, bolts attaching the bearing-plate to the horizontal head of the metal post, a rotatable disk on the plate, a center bolt passing through the plate and disk, and a gate-carrying post secured to the disk, substantially as described.

5. The combination of a stationary bearing-plate, a rotatable disk thereon, a center bolt or pin connecting the plate and disk, a gate-post mounted on the disk, a shaft journaled at the upper end of the post and having a winding drum or windlass, the series of slats pivoted at one end to the gate-post and at the other end to an upright, and connections between the windlass and the gate, substantially as described.

6. The combination of a lower stationary bearing-plate, a rotatable disk mounted thereupon, a gate-post rigidly secured to said rotatable disk, two series of slats pivoted at their inner ends to the post and at their outer ends to uprights, a windlass or drum at the upper end of the gate-post, and chains connecting the uprights with the windlass or drum, substantially as described.

7. The combination of the stationary bearing-plate, the rotatable disk thereon, and a center bolt or pin connecting the plate and disk, with a gate-post rigidly secured to the disk, two series of slats pivoted at their inner ends to the post and at their outer ends to uprights, a windlass or drum at the upper end of the post, and chains or cords connecting the uprights with the windlass or drum, substantially as described.

8. The combination of a lower stationary bearing-plate, a rotatable disk mounted thereupon, a gate post rigidly secured to said rotatable disk, two series of slats pivoted at their inner ends to the post and at their outer ends to uprights, a crank-shaft journaled at the upper end of the post, a windlass or drum on said shaft, and chains connecting the uprights with the windlass or drum, substantially as described.

In testimony whereof I affix my signature in presence of two witnesses.

JOS. ELCOCK.
